UNITED STATES PATENT OFFICE.

HARRY OGLESBY, OF CHESTER, PENNSYLVANIA.

WINDOW-SHADE ADJUSTER.

1,017,452.

Specification of Letters Patent. Patented Feb. 13, 1912.

Application filed March 24, 1911. Serial No. 616,761.

To all whom it may concern:

Be it known that I, HARRY OGLESBY, a citizen of the United States, residing at Chester, in the county of Delaware and State of Pennsylvania, have invented certain new and useful Improvements in Window-Shade Adjusters, of which the following is a specification.

This invention relates to that class of devices which are designed to let window-shades down from the top.

It is often desirable to open a window at the top, and yet, to have the lower portion screened. But shades mounted upon rollers having bracket bearings permanently fixed at the top of the windows, as usual, would prevent the free passage of air.

Therefore, the object of this invention is to provide means for vertically adjusting the brackets and the shades supported thereby.

To this end, my invention consists in the construction and combination of parts forming a window-shade adjuster, hereinafter more fully described and particularly set forth in the claim, reference being had to the accompanying drawings in which—

Figure I is a front view of a window shade showing my adjusting device in service. Fig. II shows my invention in fragmentary, side elevation, partly in section. Fig. III shows a transverse section at line x of Fig. II. Fig. IV shows an extension rod and lug.

A rail 5, having side flanges 6, forming a T-shaped body, is to be secured by suitable screws 7, to the casing at each side of the window. Brackets 8, which may be of the usual form for shade roller bearings, are slidably mounted on the rails 5, their inward extending flanges 9, passing under the rail flanges 6, to keep the brackets in standing position. The rails 5, should be long enough to extend from the top of the window down within reach of a person standing on the floor. A rod 10, is rigidly secured to each bracket 8, and extends down through a lug 11, which is in line of the rail and may be fixed thereto as shown. To the lower end of the rod 10, a box 12, is secured to carry a latch 13, and its spring 14. The latch is hung to oscillate in the box upon a pin 26, and is shaped with a hook 15, to engage the lug 11. The spring 14, actuates the hook normally into engagement. A

stop-guide 16, is mounted to slide upon the rail 5, like the bracket 8, and is provided with a binding screw 17, adapted to enter any one of the spot-holes 18, in the rod, and thereby be held rigidly to the rod.

The operation is as follows. A shade 19, being mounted by its roller 20, in the brackets 8, the operator presses upon the lower ends of the latches 13, disengaging their hooks 15, from the lugs 11, then he lowers the rods 10, and the brackets thereon until the stop guides 16, rest on the lugs 11. Corresponding spot holes 18, in the two rods being at the same distance from the brackets, the rods will hold the curtain roller level. There may be a number of spot holes 18, in each rod, to set the curtain at any height desired. For use with very high windows, extension rods 21, Fig. IV, are provided with sockets 22, to engage the rods 10, in place of the boxes 12, and these boxes are then to be attached at 23, to the rods 21. This requires another lug 24, to serve like the lug 11, secured in line of the rail 5, to the window casing, in any suitable manner, as by the screws 25. As these adjusting fixtures may be easily substituted for the common brackets, one reason for making the rods in sections is to keep all the parts short enough to be admitted to the United States mails so that the device may be supplied by a mail order business. This window shade adjuster being strong, light, of simple construction and inexpensive, will economically serve a purpose of much advantage.

I claim,

1. In a window shade adjuster, T-shaped rails to be located at the sides of the window; lugs located in line of the rails; shade-hanging brackets slidably mounted on the rails; a rod having spot-holes in it, secured to each bracket and fitted to slide through one of the said lugs; a box secured upon each rod; a latch and a spring therefor mounted in each box and adapted to engage one of the said lugs; a stop-guide slidably mounted on each rail and adjustable along one of the said rods; and a binding-screw in each stop-guide, adapted to engage any one of the spot-holes therein, the same lug being engaged by the said latch to hold the shade in its normal position, and by the said stop-guide to hold the shade when lowered.

2. In a window shade adjuster, rails to be located at the sides of the window; a lug to

be located in line of each rail; a shade-hanging bracket mounted to slide on each rail and provided with a rod which extends through the said lug; a spring latch mounted on the end of the rod and adapted to engage one of the said lugs; and a stop-guide to engage the same lug slidably mounted on a rail and the adjacent rod, and means for securing this stop-guide at definite points

upon the rod, substantially as shown and 10 described.

In testimony whereof I affix my signature in presence of two witnesses.

HARRY OGLESBY.
